US0D1048849S

(12) **United States Design Patent** (10) Patent No.: **US D1,048,849 S**
(45) Date of Patent: ** Oct. 29, 2024

(54) **TOOL HANDLE**

(71) Applicant: **LOWE'S COMPANIES, INC.**,
Mooresville, NC (US)

(72) Inventors: **Brian Joseph Demers**, Huntersville,
NC (US); **Joseph Allen Berlepsch**,
Mooresville, NC (US)

(73) Assignee: **LOWE'S COMPANIES, INC.**,
Mooresville, NC (US)

(**) Term: **15 Years**

(21) Appl. No.: **29/833,399**

(22) Filed: **Apr. 4, 2022**
